UNITED STATES PATENT OFFICE.

WALTER JÖRGENSEN, OF STOCKHOLM, SWEDEN, ASSIGNOR TO AKTIEBOLAGET SEPARATOR,
OF STOCKHOLM, SWEDEN, A COMPANY.

SPINDLE-BEARING FOR CENTRIFUGAL SEPARATORS.

No. 864,470.

Specification of Letters Patent.

Patented Aug. 27, 1907.

Application filed June 28, 1906. Serial No. 323,770.

To all whom it may concern:

Be it known that I, WALTER JÖRGENSEN, a subject of the Emperor of Russia, residing at 8 Fleminggatan, Stockholm, Sweden, have invented certain new and useful Improvements in Spindle-Bearings for Centrifugal Separators; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

My invention relates to supports for the spindle of centrifugal separators in which the bowl shaft is fixed to the bowl and coupled to the lower driving spindle, said driving spindle turning with its lower end on a pair of tread-wheels rolling in a bearing secured at the upper end of the bottom screw. In such devices it is of utmost importance that the touching parts of the driving spindle and the tread wheels exactly maintain their geometrical form, because, if not, the run of the machine becomes noisy, owing to the fact that the vibrations occurring in the frame then become quite considerable. The irregularity of the touching surfaces essentially arise in consequence of the wearing of the touching parts but also on account of an improper fitting in of the centrifugal bowl and its shaft upon the lower driving spindle.

My invention relates to an improvement, by which the said inconvenience may be avoided. I attain this result by inserting a spring connection between the driving spindle and the part turning on the tread-wheels.

My invention is illustrated on the annexed drawing, in which

a is the lower part of the driving spindle to which the bowl-shaft is connected by means of a coupling device, not shown on the drawing. The driving spindle is provided with a central socket, in which the steel-point *b* is fitted. This socket is somewhat enlarged downwards, and in the space between the wall of said socket and the steel-point *a* a spiral spring *c* is fitted pressing with its upper end against the bottom of the socket and with its lower end against the head *d* of the steel-point. This head is adapted to turn on a pair of tread-wheels *e*, *e* rolling with their shafts in bearings secured to the bottom-screw *g*. In the vertical wall of the socketed portion of the spindle *a* is the orifice *h*.

In this orifice is the pin *i* which is secured to the point *b*. This orifice *h* does not extend entirely around the spindle, therefore the spindle and point revolve together. The slot, however, is of greater width than the width of the pin and hence the point and spindle can have a relative movement.

I do not intend to limit myself to the particular type of spring shown.

If the under surface of the head of the steel-point is not perfectly even or if the tread-wheels occupy an eccentric position or are of irregular form, vibrations arise in the driving spindle and the frame. As by means of the above described spring device the steel-point has the opportunity to vibrate in a vertical direction, the former vibrations are equalized and the run of the machine becomes equal and silent.

What I claim is:

1. In combination, a driving spindle for a centrifugal separator, having a socket, a steel point located in said socket, said steel point having a head, tread wheels upon which said head rests, and a spring in said socket bearing against the wall of said socket and the head of said point, whereby said point has a yielding vertical movement. 65

2. In combination, a driving spindle for a centrifugal separator, having a socket, a steel point located in said socket, said steel point having a head, tread wheels upon which said head rests, a spring in said socket bearing against the wall of said socket and the head of said point, whereby said point has a yielding vertical movement, and a connection between said point and spindle whereby the point revolves with the spindle. 75

3. In combination, a driving spindle for a centrifugal separator, having a socket, a steel point located in said socket, said steel point having a head, tread wheels upon which said head rests, a spring in said socket bearing against the wall of said socket and the head of said point, whereby said point has a yielding vertical movement, and a connection between said point and spindle whereby the point revolves with spindle, but the spindle and point can have a relative vertical movement. 80

4. In combination a driving spindle for a centrifugal machine, said spindle having a socket, a steel-point resting loosely in said socket, said steel-point having a head, a spring in said socket bearing against the walls of said socket and the head of said point, and tread-wheels upon which said head rests. 90

In testimony that I claim the foregoing as my invention, and have signed my name in presence of two subscribing witnesses.

WALTER JÖRGENSEN.
